UNITED STATES PATENT OFFICE.

GIOVANNI FERRUZZI, OF NEW YORK, N. Y.

AMPHIBIAN FLYING MACHINE.

Application filed February 18, 1928. Serial No. 255,331.

This invention relates to flying machines of the heavier than air type and more particularly refers to an aeroplane of a novel and improved construction adapted to travel 5 both in air and in water and affording unusual conditions of safety and stability.

The primary object of this invention is to provide a flying machine of a novel and improved design, providing ample and 10 modious accommodation for a number of passengers together with conditions of stability which insure its safe travel.

Another object of this invention is to provide a novel and improved type of flying 15 machine which by virtue of its construction is bound to maintain its normal position under all conditions, its low center of gravity preventing the possibility of its tilting and nose diving, such as now exists in most 20 flying machines of the heavier than air type.

A further object is to provide, in a machine of the character specified, a novel and improved arrangement of wings and supporting planes, providing an ample supporting surface and at the same time affording simple and convenient means for effecting turning movements and for controlling ascensional and descending movements of the machine.

30 A still further object is to provide in a machine of this type, a novel and improved arrangement of the body structure affording ample accommodation for stores and passengers and at the same time lending itself for safe and comfortable travel both 35 on water and in air.

With these and other objects in view as will more fully appear as the description proceeds, this invention furthermore comprises certain novel constructions and arrangement of parts as will be hereinafter described and claimed in the appended claims.

An embodiment of my invention is illus- 45 trated in the accompany drawings, in which:

Fig. 1 is a front perspective of my im- 40 proved flying machine;

Fig. 2 is a perspective view from the side thereof;

50 Fig. 3 is a plan view of the machine;

Fig. 4 is a sectional plan view through line 4—4 of Fig. 5; and

Fig. 5 is a sectional elevation of the ma- 55 chine through line 5—5 of Fig. 3.

My improved machine consists essentially 55 of a twin body comprising two aeroplane fuselages 10, 11, connected in a substantially parallel but spaced relation by a central frame or structure 12. This frame forms an open longitudinal chamber 13, interposed 60 between the two fuselages, in which is mounted a motor housing surrounding a central motor, not shown, and provided with a pit 15 through which a mechanic can have access to the motor, said pit being prefer- 65 ably also adapted to provide a seat for a mechanic when one is carried besides the two pilots who are seated, one in each cock- 70 pit 16, 17, with which the fuselages are pro- vided in the usual manner.

The front end of each fuselage carries another motor, not shown, so that the power plant consists of a central motor and two additional motors, one at each side thereof, 75 said motors driving propellers 18, 19, 20, respectively.

The front end of chamber 13 is equipped 80 with a horizontal rudder 21 and a vertical rudder 22 which are operated independently of one another in any well known manner. The rear end of chamber 13 and the rear 85 end of each fuselage on the other hand, are provided with vertical and horizontal fins or surfaces, such as 23, 24, 25, 26, 27, 28, which serve to increase the stability of the 90 structure and which also assist the supporting action of the wings.

The wings and other parts of the sup- 95 porting structure are carried by the upper part 29 and the lower part 30 of frame 12, and the same comprise essentially a pair of stationary laterally extending wings 31, 32, mounted on the upper part 29 of frame 12 and two stationary preferably bifurcated lower wings 33, 34, laterally extending from the lower part 30 of frame 12. The upper and lower wings so far mentioned are reinforced and connected by upwardly di- 100 rected struts 35, 36, 37, 38, after the fashion now currently in use in aeroplanes of the biplane type.

In front of the upper stationary wings 31, 32 are provided two additional support- 105 ing surfaces 39, 40, laterally extending from the center of the structure and pivotally mounted at said point on a longitudinal pivot 41. Said surfaces can therefore be inclined more or less upwardly from their

horizontal position, their angular movements in this respect being controllable independently of each other.

This can be done in any well known manner, for instance, by holding down the pivotally mounted surfaces by means of cables 42, 43, respectively, against the air pressure from underneath, and by releasing one or the other cable to effect a tilting movement of one or the other surface as may be desired; so that in this manner, the surfaces may be independently or simultaneously caused to assume a direction upwardly inclined at any desired angle, such as for instance, as indicated at 39', 40'. By virtue of this arrangement, it is possible to raise one or the other surface from its normal position so as to effect turning movements of the machine at the will of the pilot in charge, said movement being preferably effectuable by either pilot.

In the preferred construction, the machine is also provided with two similar supporting surfaces 43, 44, at the rear of stationary wings 31, 32, said supporting surfaces laterally extending from and being pivotally mounted at the center of the structure on a longitudinal pivot 45. Said additional supporting surfaces 43, 44 are also inclinable upwardly independently of each other, in the same manner as explained in connection with surfaces 39, 40.

In so far as explained, the structure consists of a bimotored or preferably trimotored plane, comprising two spaced fuselages, connected by a central frame structure and provided with a special arrangement of wings and supporting surfaces. This structure is completed by equipping the upper part 29 and the lower part 30 of frame 12 with a system of auxiliary planes 46, 47, 48, 49, mounted on transversely directed pivots 50, 51, 52, 53, respectively, which are in alignment with upper part 29 and lower part 30 of frame 12, but which can be operated by either pilot to decrease or increase the angle of incidence of the structure as a whole.

This can be done in any suitable manner and to illustrate the idea the upper auxiliary planes 46, 47 are shown connected to the lower planes 48, 49 by connections 54, 55, respectively, said connections being in their turn joined by a longitudinal beam or bar 56, mounted on a shaft 57, running transversely of frame 12 and provided with a control lever 58 at each end within reach of the pilots.

By virtue of this arrangement, and by referring to Fig. 5 of the drawings, it will be understood that if lever 58 is angularly moved in a clockwise direction, the four planes 46, 47, 48, 49 will be tilted about their respective pivots, so as to provide downwardly directed surfaces, decreasing the an-

gle of incidence of the supporting structure as a whole; and on the other hand, if lever 58 is angularly moved in a counter-clockwise direction, the four planes 46, 47, 48, 49 will be tilted about their pivots so as to increase the angle of incidence and therefore the ascensional thrust on the structure.

In the first case, the machine will be caused to land, and in the second case, the machine will be caused to ascend by proper manipulation of planes 46, 47, 48, 49.

When a start of the machine is effected, planes 46, 48 may be inclined upwardly, and planes 47, 49, may be inclined downwardly about their pivots to such an extent that rapid ascent will be effected at a comparatively wide angle to the ground surface, so that a very short run will be required to start the machine; this is an obvious advantage which does away with the limitations met with the operation of flying machines of the ordinary type which require specially prepared starting and landing fields if their safe operation is to be attained.

For the same reason it is also possible to effect landings with comparatively short runs, whenever conditions so require.

The structure described, is designed for ample propelling power and has ample lifting and supporting capacity, so that the under structure which also forms a part of the present invention can be attached to or suspended from the lower part 30 of frame 12 in order to complete the novel machine forming the object of my invention.

Said under structure consists of two spaced longitudinally directed boats or pontoons 59, 60, connected by a central platform 61, upon which is built a preferably closed structure 62, providing living, seating and observation accommodation for a number of passengers which may be carried according to the capacity of the machine. Such a structure affords a commodious space which may be subdivided into various rooms, if desired, and which enjoys an unobstructed view on all sides and a relative freedom from the noise of the motors overhead.

The floor of the structure can be made of or provided with transparent panes affording an unobstructed view of the country over which the machine flies.

The decks of the boats or pontoons, which extend alongside the central structure 62 afford in their turn an ample and commodious space, wherein the passengers may walk or sit in the open air, the same being used practically in the same way as the deck of an ordinary steamship; walking space may also be provided by the lower wings 33, 34, said surfaces being reached by means of a ladder or other suitable means such as shown at 63 in Fig. 2.

The boats or pontoons are each provided

with a relatively deep keel 64, 65, affording supports for wheels 66, 67, mounted on laterally extending pivots such as 68, said wheel projecting to some extent below the lower edge of the keels.

By virtue of this arrangement, the wheels are enabled to provide a roller support for the entire structure, and the keels in their turn go to insure the stability of the structure when landing in water, preventing excessive rolling movements thereof.

The sides of the boats or pontoons may be equipped with stairways, such as shown at 69, which may be lowered to the water edge 15 or raised therefrom, if desired. The various parts of the structure may be connected and reinforced by cables or chains 70, 71, 72, and so forth, wherever it may be useful or desirable in order to form a strong and resis- 20 tant structure.

The complete machine thus described is therefore well adapted to provide safe and comfortable travel for a number of passengers, at the same time providing ample and 25 easily accessible room for the storage of merchandise and supplies in the holds of the two boats or pontoons. The under structure serves to a certain extent to increase the stability of the machine by lowering its center 30 of gravity, so that under no conditions will the machine turn over.

An additional factor of safety is provided by the fact that the machine is equipped with a multimotored plant, this being the recognized 25 practice, wherever safety and reliability of operation are the primary considerations.

The machine as designed, is equally well adapted to travel through air and on water, 40 its sea worthiness being warranted by the twin body construction of its lower structure and by the relatively deep keels with which the boats or pontoons are provided.

In addition to this, as stated, the machine 45 is capable of relatively rapid ascensional and descent movements, due to the arrangement of pivotally mounted planes 46, 47, 48, 49, and the same is furthermore capable of rapid turning movements due to the possibility of 50 independently controlling inclinable surfaces 39, 40, 43, 44.

The machine is especially suitable for 55 transportation of merchandise and passengers, but can also be used for defensive and offensive purposes in war service; in this event, defensive and offensive means of any suitable description may be provided and guns may be mounted on the decks as shown, for instance at 73 while torpedoes and other 60 weapons may be suspended from the bottom of the center structure 62.

Various details of construction of my invention may be modified to a certain extent without departing from the scope of my 65 inventive idea; therefore, the drawings

should be understood as being intended for illustrative purposes only and not in a limiting sense. I accordingly reserve myself the right to carry my invention into practice in all those ways and manners which may 70 enter, fairly, into the scope of the appended claims.

I claim:

1. In a flying machine the combination of two spaced fuselages each provided with a 75 motor, stationary supporting planes therefor, additional planes vertically tilttable on horizontal longitudinal axes, a horizontal and a vertical rudder, a lower body structure comprising two spaced boats, a frame 80 mounted on said two boats and supporting said fuselage and planes, a platform connecting said two boats and bridging the space therebetween, and a cabin mounted on said platform. 85

2. In a flying machine the combination of a wing structure of the biplane type comprising fixed wings, and additional wings vertically tilttable about horizontal longitudinal axes, two spaced fuselages each provided with a motor, associated with said wing structure, a third motor mounted therebetween, a lower body structure comprising two boats, a frame connecting said two boats and supporting said fuselages and wing 90 structure and a vertical and a horizontal rudder mounted on said frame. 95

3. In a flying machine the combination of two spaced fuselages each provided with a motor, stationary supporting planes therefor, additional planes vertically tilttable on horizontal longitudinal axes, longitudinal planes vertically tilttable about horizontal transversal axes, a horizontal and a vertical rudder, a lower body structure comprising 100 two spaced boats, a frame mounted on said two boats and supporting said fuselage and planes, and a cabin also mounted on said boats. 105

4. In a flying machine the combination of a wing structure of the biplane type comprising fixed wings, and additional wings vertically tilttable about horizontal longitudinal axes, longitudinal planes vertically tilttable about horizontal transversal axes, two 115 spaced fuselages each provided with a motor, associated with said wing structure, a third motor mounted therebetween, a lower body structure comprising two boats, a frame connecting said two boats and supporting said 120 fuselages and wing structure and a vertical and a horizontal rudder mounted on said frame.

5. In a flying machine the combination of a wing structure of the biplane type comprising fixed wings and additional wings vertically tilttable about horizontal longitudinal axes, two spaced fuselages each provided with a motor, associated with said wing structure, a third motor mounted 125 130

therebetween, longitudinal planes vertically tilttable about horizontal transversal axes also mounted between said two fuselages, a lower body structure comprising two boats each provided with a knife-like keel, wheels mounted on said keels projecting beyond the lower edge thereof, a frame connecting said two boats and supporting said fuselages and wing structure, and a vertical and a horizontal rudder mounted on said frame.

6. In a flying machine the combination of a wing structure of the biplane type comprising fixed wings and additional wings vertically tilttable about horizontal longitudinal axes, two spaced fuselages each provided with a motor, associated with said

wing structure, a third motor mounted therebetween, longitudinal planes vertically tilttable about horizontal transversal axes also mounted between said two fuselages, a lower body structure comprising two spaced boats each provided with a knife-like keel, wheels mounted on said keels projecting beyond the lower edge thereof, a frame mounted on said boats and supporting said fuselages and wing structure, a vertical and a horizontal rudder mounted on said frame, a platform connecting said two boats and bridging the space therebetween and a cabin mounted on said platform. 20 25

GIOVANNI FERRUZZI.
